DRAFT CONTROLLING DEVICE

Hal M. Cunningham, Branford, Conn.

Application February 8, 1946, Serial No. 646,398

6 Claims. (Cl. 236—45)

1

This invention relates to improvements in draft controlling devices and more particularly to improvements in automatic draft controls of the form shown in Patent No. 2,251,440 issued August 5, 1941, and entitled Furnace flue damper.

In draft control devices of the above nature it is particularly desirable that the face of the draft control plate of the device be disposed in a vertical plane and that the frame holding this plate be snugly engaged against the open end of the flue extension to prevent rocking movement. It is also particularly desirable that the frame and flue extension be firmly secured together to prevent them separating should sudden pressure be developed in the flue. It is also desirable that the connection between the frame and the flue extension be conveniently and readily connected and disconnected to permit efficient attachment of the device to existing installations, and to allow adjustments, of the device in respect to the flue extension to be conveniently and quickly made.

The objects of this invention are: to provide means in a draft controlling device of the above nature to insure proper location assembly of the device to a flue extension; to provide efficient means to connect the frame of the device to the flue extension which can be readily and conveniently actuated; and to provide an improved form of holding frame for the operating damper plate of the device whereby the device locating means and the frame connecting means are efficiently and conveniently associated with other structural features of the device.

A further object of this invention is to provide an improved draft control device which will be relatively inexpensive to manufacture, simple in construction, pleasing in appearance, compact, and very efficient and durable in use.

With these and other objects in view, which will appear as the description proceeds, there has been illustrated in the accompanying drawings a form in which the features and principles of this invention may be conveniently and practically embodied.

In the drawings:

Figure 1 is a front view of a portion of a flue pipe having a flue extension attached thereto and shows an edge view of a draft control device embodying the features and principles of this invention secured to the open end of the flue extension;

Figure 2 is an enlarged inside face view of the draft control device of this invention and is a sectional view taken on the line 2—2 of Figure 1;

2

Figure 3 is an enlarged sectional view of the device taken on line 3—3 of Figure 2;

Figure 4 is a still further enlarged broken sectional view of the frame and flue extension connecting means; and

Figure 5 is an enlarged broken sectional view of the frame and flue extension locating means taken on line 5—5 of Figure 2.

Referring now to the drawings wherein like reference numerals designate like parts throughout the several views, the reference numeral 11 denotes a section of a flue pipe which connects a combustion chamber (not shown) with a chimney or stack (not shown) to carry away burned gases and in which there is a continuous draft of constantly varying degrees of intensity. As specifically pointed out in the above referred to Patent 2,251,440, the draft control device comprises a frame 12 adapted to be secured to a flue extension 13 which in turn is attached to the flue pipe 11 over a suitably formed opening (not shown) provided in the flue pipe 11 in any convenient section thereof between the combustion chamber and the stack.

25 A plate 14 is pivoted to the frame 12 to substantially cover a central opening therein when in closed position, it being urged into such closed position by an adjustable weight 15. A flat leaf spring 16 is secured to the frame 12 and extends over the rear face of the draft controlling plate into position to be engaged by the weight 15 to limit its opening movement of the plate 14. A pocket 17 is provided in the frame 12 in communication with the atmosphere outside of the flue pipe 11 and is positioned to be covered by the plate 14 when the latter is in closed position. The pocket 17 is an essential element of the draft control device and its function is particularly pointed out in the above referred to patent.

The improved frame 12 of this invention is preferably cast, or otherwise formed, in one piece and comprises an annular flat rim portion 18 having a central opening 19, an annular flange 21 extending rearwardly from the front face of the rim portion 18 about the periphery of the opening 19, and an annular flange 22 extending rearwardly from the front face of the trim portion 18 about the outer periphery thereof. The rim portion 18 with the spaced apart flanges 21 and 22 forms a frame substantially U-shaped in cross-section whereby the same will be of substantial strength and the possibility of it warping will be eliminated. A portion of the flange 21 forms one wall of the pocket 17. A rear face wall 23 extends from the flange 21 toward the

center of the frame 12 and a wall 24 extends from the rear face wall 23 of the pocket outwardly to adjacent the plane of the front face of the rim portion 18.

The flange 21 extends rearwardly a greater amount than does the flange 22 and is of the proper dimensions to snugly enter the open outer end 25 of the flue extension 13. To properly locate the frame 12 squarely against the end of the flue extension 13, and to strengthen by cross-bracing the flanges 21 and 22, a plurality of filler pieces 26, 27, 28, and 29 are peripherally spaced apart about the rim portion 18 between the flanges 21 and 22. The rear faces 31 of the aforesaid filler pieces are aligned in the same plane, which is parallel to the front face of the rim 18, so that the end edge of the flue extension 13 will seat against all of the said rear faces 31 and locate the frame 12 in proper position thereon.

The filler pieces 26 and 28 are disposed diametrically opposite each other and each have a threaded hole 32 formed therein to receive a threaded bearing member 33. The inner ends of the bearing members 33 have a pivot stud 34 formed thereon adapted to be received into a hole formed in the end of a rod 35 secured to the plate 14 thereby forming a pivotal support for the plate 14.

The peripherally spaced apart filler pieces 27 and 29 have lugs 36 and 37 extending rearwardly respectively therefrom. The lugs 36 and 37 are spaced outwardly from the flange 21 to permit the edge of the end 25 of the flue extension 13 passing therebetween to seat upon the filler pieces 27 and 29. A threaded hole is provided in each of the lugs 36 and 37 to receive a threaded clamp member 38 which, when screwed inwardly toward the flue extension 13 clamps it firmly against the outer surface of the flange 21. If desired, the clamp member 38 is provided with a rounded end 39 to inset into the material of the flue extension 13 or, as shown, the flange 21 may be countersunk as at 41 opposite the rounded end 39 of the member 38 whereby, upon clamping the flue extension, its material at this point will be depressed into the countersink 41 and detachably locked in place. The clamp members 38 are provided with a screw driven slot 42 in their ends which are conveniently reached for attaching or disconnecting the frame 12 from the flue extension 13, or to adjust the frame 12 about the flue extension 13.

A platform 43 having an inwardly facing surface 44 disposed at an angle to the inner face of the pocket rear wall 23 is provided upon said pocket rear wall to support the leaf spring stop member 16. Flanges 45 and 46 are formed along either side of the platform 43 to locate the spring member 16 and hold it against turning upon its fastening member which member comprises a lug 47 extending through the member 16 from the platform 43 and riveted over upon the member 16.

The draft control device, improved by the inclusion in its structure of the one-piece frame member 12 having the structural features above described, is especially efficient in operation and particularly practical to install and adjust. The provision of the filler pieces 26, 27, 28, and 29 whereby the frame 12 may be accurately located upon the end of the flue extension 13 and form cross braces for the flanges 21 and 22, result in a strong frame structure which is practically free from undesirable warping. The provision of the

clamping members 38 conveniently accessible from outside of the device, permits quick and efficient attachment or adjustment of the device into operative position.

While there has been shown and described herein one form in which the features and principles of this invention may be conveniently embodied in practice, it is to be understood that the same may be embodied in other specific forms without departing from the spirit and essential attributes thereof, and it is therefore desired that the present embodiment be considered in all respects as illustrative and not restrictive, reference being had to the claims rather than to the foregoing description to indicate the scope of the invention.

Having thus fully disclosed the invention, what is claimed as new and for which it is desired to secure Letters Patent, is:

20. 1. In a draft controlling device, a frame member having a central opening, a damper plate pivoted to said frame member within the opening therein, said frame member having a flat rim portion, and an annular flange extending rearwardly and substantially at right angles from the rim portion about the periphery of the central opening therein and being adapted to enter the open end of a flue extension, lugs spaced apart about the periphery of the flange, extending rearwardly from the rim portion, and being spaced laterally from the flange to allow the end of the flue extension to be disposed therebetween, and means supported by said lugs to clamp the flue extension against said flange.
25. 2. In a draft controlling device, a frame member having a central opening, a damper plate pivoted to said frame member within the opening therein, said frame member having a flat rim portion and an annular flange extending rearwardly and substantially at right angles from the rim portion about the periphery of the central opening therein and being adapted to enter the open end of a flue extension, lugs spaced apart about the periphery of the flange, extending rearwardly from the rim portion, and being spaced laterally from the flange to allow the end of the flue extension to be disposed therebetween, and threaded means supported by said lugs to clamp the flue extension against said flange.
30. 3. In a draft controlling device, a frame member having a central opening, a damper plate pivoted to said frame member within the opening therein, said frame member having a flat rim portion and an annular flange extending rearwardly and substantially at right angles from the rim portion about the periphery of the central opening therein and being adapted to enter the open end of a flue extension, lugs spaced apart about the periphery of the flange, extending rearwardly from the rim portion, and being spaced laterally from the flange to allow the end of the flue extension to be disposed therebetween, and threaded means screw-threaded through each of said lugs to engage the flue extension end and clamp it against said flange, a countersink in said flange in axial alignment with each of said threaded means, said threaded means having a rounded end whereby the material of said flue extension where clampingly engaged thereby will be pressed into the said countersinks to lock the frame member to the flue extension to prevent relative rotation thereof.
35. 4. In a draft controlling device, a frame member having a central opening, a damper plate pivoted to said frame member within the opening therein, said frame member having a flat rim portion and an annular flange extending rearwardly and substantially at right angles from the rim portion about the periphery of the central opening therein and being adapted to enter the open end of a flue extension, a second flange extending rearwardly about the periphery of said rim portion and spaced laterally from the first mentioned flange, filler pieces extending between said flanges and being spaced apart peripherally about said rim portion, the rear faces of said filler pieces being in the same plane to be engaged by the end edge of the flue extension to locate the frame rim parallel to the end edge of the flue extension, lugs extending
40. 5. In a draft controlling device, a frame member having a central opening, a damper plate pivoted to said frame member within the opening therein, said frame member having a flat rim portion and an annular flange extending rearwardly and substantially at right angles from the rim portion about the periphery of the central opening therein and being adapted to enter the open end of a flue extension, a second flange extending rearwardly about the periphery of said rim portion and spaced laterally from the first mentioned flange, filler pieces extending between said flanges and being spaced apart peripherally about said rim portion, the rear faces of said filler pieces being in the same plane to be engaged by the end edge of the flue extension to locate the frame rim parallel to the end edge of the flue extension, lugs extending
45. 6. In a draft controlling device, a frame member having a central opening, a damper plate pivoted to said frame member within the opening therein, said frame member having a flat rim portion and an annular flange extending rearwardly and substantially at right angles from the rim portion about the periphery of the central opening therein and being adapted to enter the open end of a flue extension, a second flange extending rearwardly about the periphery of said rim portion and spaced laterally from the first mentioned flange, filler pieces extending between said flanges and being spaced apart peripherally about said rim portion, the rear faces of said filler pieces being in the same plane to be engaged by the end edge of the flue extension to locate the frame rim parallel to the end edge of the flue extension, lugs extending
50. 7. In a draft controlling device, a frame member having a central opening, a damper plate pivoted to said frame member within the opening therein, said frame member having a flat rim portion and an annular flange extending rearwardly and substantially at right angles from the rim portion about the periphery of the central opening therein and being adapted to enter the open end of a flue extension, a second flange extending rearwardly about the periphery of said rim portion and spaced laterally from the first mentioned flange, filler pieces extending between said flanges and being spaced apart peripherally about said rim portion, the rear faces of said filler pieces being in the same plane to be engaged by the end edge of the flue extension to locate the frame rim parallel to the end edge of the flue extension, lugs extending
55. 8. In a draft controlling device, a frame member having a central opening, a damper plate pivoted to said frame member within the opening therein, said frame member having a flat rim portion and an annular flange extending rearwardly and substantially at right angles from the rim portion about the periphery of the central opening therein and being adapted to enter the open end of a flue extension, a second flange extending rearwardly about the periphery of said rim portion and spaced laterally from the first mentioned flange, filler pieces extending between said flanges and being spaced apart peripherally about said rim portion, the rear faces of said filler pieces being in the same plane to be engaged by the end edge of the flue extension to locate the frame rim parallel to the end edge of the flue extension, lugs extending
60. 9. In a draft controlling device, a frame member having a central opening, a damper plate pivoted to said frame member within the opening therein, said frame member having a flat rim portion and an annular flange extending rearwardly and substantially at right angles from the rim portion about the periphery of the central opening therein and being adapted to enter the open end of a flue extension, a second flange extending rearwardly about the periphery of said rim portion and spaced laterally from the first mentioned flange, filler pieces extending between said flanges and being spaced apart peripherally about said rim portion, the rear faces of said filler pieces being in the same plane to be engaged by the end edge of the flue extension to locate the frame rim parallel to the end edge of the flue extension, lugs extending
65. 10. In a draft controlling device, a frame member having a central opening, a damper plate pivoted to said frame member within the opening therein, said frame member having a flat rim portion and an annular flange extending rearwardly and substantially at right angles from the rim portion about the periphery of the central opening therein and being adapted to enter the open end of a flue extension, a second flange extending rearwardly about the periphery of said rim portion and spaced laterally from the first mentioned flange, filler pieces extending between said flanges and being spaced apart peripherally about said rim portion, the rear faces of said filler pieces being in the same plane to be engaged by the end edge of the flue extension to locate the frame rim parallel to the end edge of the flue extension, lugs extending
70. 11. In a draft controlling device, a frame member having a central opening, a damper plate pivoted to said frame member within the opening therein, said frame member having a flat rim portion and an annular flange extending rearwardly and substantially at right angles from the rim portion about the periphery of the central opening therein and being adapted to enter the open end of a flue extension, a second flange extending rearwardly about the periphery of said rim portion and spaced laterally from the first mentioned flange, filler pieces extending between said flanges and being spaced apart peripherally about said rim portion, the rear faces of said filler pieces being in the same plane to be engaged by the end edge of the flue extension to locate the frame rim parallel to the end edge of the flue extension, lugs extending
75. 12. In a draft controlling device, a frame member having a central opening, a damper plate pivoted to said frame member within the opening therein, said frame member having a flat rim portion and an annular flange extending rearwardly and substantially at right angles from the rim portion about the periphery of the central opening therein and being adapted to enter the open end of a flue extension, a second flange extending rearwardly about the periphery of said rim portion and spaced laterally from the first mentioned flange, filler pieces extending between said flanges and being spaced apart peripherally about said rim portion, the rear faces of said filler pieces being in the same plane to be engaged by the end edge of the flue extension to locate the frame rim parallel to the end edge of the flue extension, lugs extending

rearwardly from at least one pair of filler pieces, said lugs being spaced laterally from the first mentioned flange to receive the end of the flue extension therebetween, and means supported by said lugs to clamp the flue extension against said first mentioned flange.

4. In a draft controlling device, a frame member having a central opening, a damper plate pivoted to said frame member within the opening therein, said frame member having a flat rim portion and an annular flange extending rearwardly and substantially at right angles from the rim portion about the periphery of the central opening therein and being adapted to enter the open end of a flue extension, a second flange extending rearwardly about the periphery of said rim portion and spaced laterally from the first mentioned flange, filler pieces extending between said flanges and being spaced apart peripherally about said rim portion, the rear faces of said filler pieces being in the same plane to be engaged by the end edge of the flue extension to locate the frame rim parallel to the end edge of the flue extension, bearing members in diametrically opposite filler pieces for said damper plate, lugs extending rearwardly from at least one pair of filler pieces, said lugs being spaced laterally from the first mentioned flange to receive the end of the flue extension therebetween, and means supported by said lugs to clamp the flue extension against said first mentioned flange.

5. In a draft controlling device, a frame member having a central opening, a damper plate pivoted to said frame member to freely swing within the opening therein, said frame member having a flat forwardly facing rim portion and an annular flange extending rearwardly and substantially at right angles from the rim portion about the periphery of the central opening therein and being adapted to enter, and be firmly received in, the open end of a flue extension, a second flange extending rearwardly about the periphery of said rim portion and spaced laterally from the first mentioned flange, filler pieces extending between said flanges and being spaced apart peripherally about said rim portion, the rear faces of said filler

pieces being in the same plane to be engaged by the end edge of the flue extension to locate the frame rim parallel to the end edge of the flue extension, lugs extending rearwardly from at least one pair of filler pieces, said lugs being spaced laterally from the first mentioned flange to receive the end of the flue extension therebetween, and threaded means screw-threaded through each of said lugs to engage the flue extension end and clamp it against said flange.

10 clamp it against said flange.

6. A frame for a draft controlling device, said frame having a flat forwardly facing circular rim portion, a first circular flange portion extending about the inner periphery of the rim portion and
15 rearwardly at right angles therefrom to define a circular opening in the frame, a second circular flange portion extending about the outer periphery of the rim portion and rearwardly at right angles therefrom, said second flange being shorter
20 in length than said first flange, peripherally spaced apart filler pieces between said flanges with their rearwardly directed faces lying in the same plane, said first flange being adapted to be snugly received within the end of a flue pipe with
25 the end edge of said pipe seated upon the rearwardly directed faces of said filler pieces, a lug extending rearwardly from diametrically opposite filler pieces with its inner face spaced outwardly from the first flange to provide a space
30 to receive the end of the flue pipe into which said first flange is inserted, and means carried by each lug to clamp the flue pipe against the first flange.
